DESIGN FOR WALL-PAPER.

SPECIFICATION forming part of Design No. 23,695, dated October 16, 1894.

Application filed September 13, 1894. Serial No. 522,945. Term of patent 3½ years.

To all whom it may concern:

Be it known that I, IVY MARIE L. TRUITT, a citizen of the United States, residing at Buffalo, in the county of Erie and State of New York, have invented and produced a new and original Design for Wall-Paper, of which the following is a specification.

The design consists of a series of wreaths of flowers and leaves of violets arranged in vertical rows and connected by flowing ribbons as represented in the accompanying drawing.

The border or upper portion of the design is formed of open wreaths of flowers and

leaves of violets connected by festoons of ribbon and is separated from the hanging by a narrow band with two interlaced ribbons running lengthwise in said band as shown in the drawing.

What I claim is—

The design for wall paper herein shown and described.

Witness my hand this 6th day of September, 1894.
